Patented Oct. 22, 1968

212,470

CHAIR

Sheldon M. Rutter, Miami, Fla., assignor to Birmingham Ornamental Iron Company, Inc., Birmingham, Ala., a corporation of Alabama

Filed Dec. 8, 1967, Ser. No. 9,710

Term of patent 3½ years

(Cl. D15—1)

FIG 1

Des. 212,470

PAGE 2

FIG. 1 is a side elevational view of a chair showing my design, the side not shown being a mirror image of the side shown.

FIG. 2 is a top plan view.

FIG. 3 is a front elevational view of the same.

I claim:

The ornamental design for a chair, as shown and described.
